UNITED STATES PATENT OFFICE.

ARTHUR R. HAVENER, OF WAYLAND, MASSACHUSETTS, ASSIGNOR TO JUDSON L. THOMSON MFG. CO., A CORPORATION OF MASSACHUSETTS.

FEEDING MECHANISM FOR RIVET AND CAP SETTING MACHINES.

1,333,414.

Specification of Letters Patent.

Patented Mar. 9, 1920.

Original application filed March 4, 1918, Serial No. 220,193. Divided and this application filed June 17, 1918. Serial No. 240,403.

To all whom it may concern:

Be it known that I, ARTHUR R. HAVENER, a citizen of the United States, residing at Wayland, in the county of Middlesex and 5 State of Massachusetts, have invented new and useful Improvements in Feeding Mechanisms for Rivet and Cap Setting Machines, of which the following is a specification.

10 This invention relates to machines for feeding disk-shaped articles such as the caps for rivets.

The object of the invention is to provide a rivet cap feeding mechanism which is simple and efficient in action.

15 The application is a division from the application of Arthur R. Havener, rivet and cap setting machine, Serial No. 220,193, filed March 4, 1918.

20 The invention consists in a cap feeding mechanism hereinafter described in the specification and particularly pointed out in the claims.

Referring to the drawings:

25 Figure 1 is a left hand side elevation of a rivet cap setting machine with my improved cap feeding instrumentalities embodied therein.

30 Fig. 2 is a longitudinal central section of said machine.

Fig. 3 is a detail plan view of the rivet cap feeding instrumentalities.

35 Figs. 4 and 5 are detail plan views similar to Fig. 3 illustrating the cap feeding instrumentalities in different positions.

Like numerals refer to like parts throughout the several views of the drawings.

In the drawings, 6 is the frame of the machine, 7 is the anvil, 8 the work-support, 9 40 the rivet driver and 10 the rivet carrier. 11 and 12 are the horizontal and inclined portions, respectively, of a raceway 13 which feeds the rivet caps from a rivet cap hopper 14 to the anvil 7.

45 The rivet caps are deposited in mass in the hopper 14 and are fed from said hopper down the inclined portion 12 of the raceway 13 until the lowermost rivet cap 15 on said inclined portion 12 of the raceway rests 50 against the upper edge of a slide 16 as illustrated in Fig. 3.

A rivet cap detent and feed finger 17 consists of an arm 18 which is pivoted at 19 to the frame of the machine and terminates in

an inclined portion 20 at its forward end, 55 said inclined portion 20 being adapted to be engaged by the front edge of the slide 16 as said slide is moving forward in a manner hereinafter described.

A plate 21 is fastened to the arm 18 and 60 said plate has a lateral wedge-shaped projection 22 thereon which is adapted to enter between the lowermost rivet cap 15 on the raceway 13 and the next to the lowermost rivet cap 23 on said raceway, so that said 65 projection 22 acts as a wedge to force the cap 15 from the inclined portion of the raceway along the horizontal portion thereof after the slide 16 has retreated sufficiently to allow this to be done, as hereinafter more 70 fully described, and at the same time the next to the lowermost rivet cap 23 is held against movement downwardly on the inclined portion of the raceway by the projection 22 on the plate 21.

75 A spring 24 is connected at one end thereof to a pin 25 and at the other end thereof to a pin 26 bearing against the frame of the machine. Said pin 25 is fast to the arm 18 and constitutes a stop pin to limit the distance to which the arm 18 can be moved by the spring 24, and when the parts are in the relative positions illustrated in Fig. 3 the free end of the arm 18 rests against the side of the slide 16.

80 The raceway 13, consisting of the inclined portion 12 and the horizontal portion 11, is formed by two parallelly disposed members 27 and 28 which have a space 29 therebetween. These members 27 and 28 are each 85 grooved at 30 and 31, respectively, upon their inner adjacent faces to receive the opposite sides of the rivet caps as they are fed along the raceway. The raceway 13 terminates at its front end in two fingers 32 and 33 pivoted at 34 and 35, respectively, to the frame of the machine and terminating at their front ends in segmental circular-shaped recesses 36 and 37 into which the rivet cap is fed when in its forward position by the slide 16.

90 The work-support 8 has a projection 38 thereon constituting a stop against which the fingers 32 and 33 abut when in the position illustrated in Fig. 3. Said fingers 105 are moved toward each other by springs 39 and 40, respectively.

A reciprocating motion is imparted to the

slide 16 by a bell-crank lever 41 which is pivoted at 42 to the frame of the machine and the vertical arm 43 of which engages an ear 44 on the slide 16. The horizontal arm 5 of said bell-crank lever has a circular shaped end 45 which enters a slot 46 in a member 47. The member 47 constitutes a link, the upper end of which is connected by a pin 48 to a lever 49 and the lower end of which 10 is mounted upon a crank 50 formed on a shaft 51 journaled to rotate in the frame of the machine.

A rotary motion is imparted to the shaft 51 by a clutch 52 which is driven from the 15 main driving shaft 53 of the machine. The ear 44 is held against the vertical arm 43 of the bell-crank lever 41 by a spring 54 connected to the vertical arm 43 of the bell-crank lever 41 at one end thereof and at 20 its opposite end is connected to an arm 55 which is fastened to the slide 16, so that the slide 16 is carried forward by the spring 54 and backward by the arm 43. The distance to which the slide 16 can be moved forward 25 is limited by a screw 56, which, when the slide has arrived at its extreme forward position, engages the frame of the machine.

The rivet setting instrumentalities, although forming no part of this invention, 30 consist of the rivet driver 9 and the anvil 7. The rivet driver has a vertical reciprocating motion imparted thereto by the lever 49 and the anvil has a vertical reciprocating motion imparted thereto by a lever 57 pivoted at 58 to the frame of the machine and having a rocking movement imparted thereto by the inclined lower edge 59 of the slide 16 which, in its forward and backward movement, engages a roll 60 journaled on 40 the rear end of the lever 57.

The general operation of the cap feeding mechanism hereinbefore described is as follows: Assuming the shaft 51 to be rotating in the direction of the arrow *a*, Fig. 2, 45 the bell-crank lever 41 will be operated to move the slide 16 rearwardly until the front end of said slide disengages the free end of the arm 18 (see Fig. 3) and said arm will then be moved by the spring 24 to the position illustrated in Fig. 4, with the wedge-shaped projection 22 projecting between and 50 pressing against the lowermost rivet cap 15 on the inclined portion 12 of the raceway 13 and against the next to the lowermost rivet cap 23 on said raceway. The lower edge of the lowermost rivet cap is now bearing 55 against the upper edge of the slide 16. Upon a further movement of said slide toward the rear the upper edge of said slide 60 will become disengaged from the rivet cap 15 and the spring 24 will then cause the arm 18 to spring forwardly into the position 65 illustrated in Fig. 5 and thus drive the rivet cap 15 forward onto and along the horizontal portion 11 of the rivet cap raceway,

while at the same time the projection 22 holds the rivet cap 23 and the column of rivet caps above the same against movement on the rivet cap raceway.

During this rearward movement of the 70 slide 16 the incline 59 on the lower edge of said slide engages the roll 60 and rocks the lever 57 to raise the anvil 7 and at the same time the lever 49 is rocked to move the driver 9 downwardly and the rivet is set in 75 the rivet cap in a manner well known to those skilled in the art, but forming no part of this invention.

During the setting of the rivet in the rivet cap, the anvil 7, during its upward 80 movement, forces the fingers 32 and 33 apart and carries the rivet cap, which at that time is held between said fingers in the segmental recesses 36 and 37, upwardly and against the lower surface of the material to which 85 the rivet and rivet cap are to be attached.

After the rivet has been set the motions of the different parts hereinbefore described will be reversed, that is, the rivet carrier and rivet driver will be moved upwardly, 90 the anvil will move downwardly, the fingers 32 and 33 will be brought toward each other by their respective springs until they engage the stop 38, and the bell-crank lever 41 will be rocked to allow the slide 16 to be moved forward by the spring 54 until the front end of said slide 16 engages the inclined end 20 of the arm 18 and pushes said arm out of the raceway slot, whereupon the projection 22 will be removed from engagement with the rivet cap 23 and said rivet cap will then slide down the inclined portion of the rivet cap raceway until its lower edge engages the upper edge of the slide 16. Meantime the rivet cap 15 which has 105 been forced onto and along the horizontal portion 11 of the raceway 13 will be engaged by the front end of the slide 16 and fed forward between the fingers 32 and 33 until it lodges in the segmental circular recesses 110 36 and 37 on the front end of said fingers and in alignment with and between the anvil 7 and the rivet carrier 10. The slide 16 will then be moved back to the position 115 illustrated in Fig. 2 and the operator will manipulate the clutch to stop the machine.

Having thus described my invention, what I claim and desire by Letters Patent to secure is:

1. A machine for feeding rivet caps having, in combination, a hopper; a raceway comprising two parallelly disposed members with grooves in their adjacent edges adapted to receive the edges of said caps, a feed slide, mechanism adapted to impart to said slide a reciprocatory motion between said members, a detent and feed finger adapted to be engaged by said slide and to enter between the two lowermost caps on said raceway in a direction substantially 120

tangential to said caps, yielding means adapted to move said feed finger transversely of said slide, whereby, when said slide is moved out of engagement with said feed finger and out from between said raceway members, the lowermost cap of said pair of caps will be forced along said raceway and the cap adjacent said lowermost cap will be held against movement on said raceway.

2. A machine for feeding rivet caps having, in combination, a hopper, a raceway having an inclined portion and comprising two parallelly disposed members with grooves in their adjacent edges adapted to receive the edges of said caps, a feed slide, mechanism adapted to move said feed slide between said members, with its upper edge in position to be engaged by the lowermost cap of a column of said caps on the inclined portion of said raceway, a detent and feed finger adapted to be engaged by said slide and to enter between the two lowermost caps on said raceway in a direction substantially tangential to said caps, and yielding means adapted to move said feed finger transversely of said slide whereby when said slide is moved out of engagement with said finger and said lowermost cap, said lowermost cap will be forced by said detent and feed finger along said raceway and the cap adjacent said lowermost cap will be held against movement on said raceway by said detent and feed finger until released by the engagement of said detent and feed finger by said slide on its return movement.

3. A machine for feeding rivet caps having, in combination, a hopper, a raceway having an inclined portion and comprising two parallelly disposed members with grooves in their adjacent edges adapted to receive the edges of said caps, a feed slide, mechanism adapted to move said slide between said members with its upper edge in position to be engaged by the lowermost cap of a column of said caps on the inclined portion of said raceway, a pivotally mounted arm terminating at its free end in an inclined portion and adapted to be engaged by said slide, a pivot for said arm normal to that part of the inclined portion of said raceway upon which said lowermost cap is adapted to rest, a projection on said arm adapted to enter between the two lowermost caps on said raceway in a direction substantially tangential to said caps, and yielding means adapted to move said arm transversely of said raceway whereby when said slide is moved out of engagement with the free end of said arm and said lowermost cap, said lowermost cap will be forced by said projection along said raceway and the cap adjacent said lowermost cap will be held against movement on said raceway by said projection until released by the en-

gagement of said inclined portion at the free end of said arm by said slide on its return movement.

4. A machine for feeding rivet caps having, in combination, a hopper, a raceway having an inclined portion and comprising two parallelly disposed members with grooves in their adjacent edges adapted to receive the edges of said caps, a feed slide, mechanism adapted to move said slide between said members with its upper edge in position to be engaged by the lowermost cap of a column of said caps on the inclined portion of said raceway, an arm terminating in an inclined portion at its free end and adapted to be engaged by said slide, a pivot for said arm normal to that part of the inclined portion of said raceway upon which said lowermost cap is adapted to rest, a plate on said arm having a wedge-shaped end adapted to enter between the two lowermost caps on said raceway in a direction substantially tangential to said caps, and yielding means adapted to move said arm transversely of said raceway whereby when said slide is moved out of engagement with said arm and said lowermost cap, said lowermost cap will be forced by said plate along said raceway and the cap adjacent said lowermost cap will be held against movement on said raceway by said plate until released by the engagement of said inclined portion of said arm by said slide on its return movement.

5. A rivet and cap setting machine having, in combination, an anvil, a stationary work-support, a raceway having an inclined portion and a horizontal portion and comprising two parallelly disposed members and a pair of spring-actuated fingers constituting the front end of said raceway and adapted to receive and hold a rivet cap, the adjacent edges of said fingers and parallelly disposed members being provided with grooves adapted to receive the edges of said rivet caps, a feed slide, mechanism adapted to impart to said feed slide a reciprocatory motion between said members and fingers, a detent and feed finger adapted to be engaged by said slide and to enter between the two lowermost rivet caps on the inclined portion of said raceway in a direction substantially tangential to said caps, and yielding means adapted to move said feed finger transversely of said slide whereby when said slide is moved out of engagement with said feed finger and out from between said raceway members, the lowermost rivet cap of said pair of rivet caps will be forced from the inclined portion of said raceway along the horizontal portion thereof and the rivet cap adjacent said lowermost rivet cap will be held against movement on the inclined portion of said raceway by said detent and feed finger.

6. A machine for feeding rivet caps hav-

ing, in combination, a hopper, a raceway having an inclined portion and a horizontally disposed portion, a slide movable transversely of said inclined portion and adapted to be engaged by the lowermost rivet cap of a column of rivet caps on said inclined portion and means operated by said slide adapted to be moved between said lowermost cap and a cap located thereabove and in contact therewith in a direction substantially tangential to said caps whereby said lowermost cap may be forced from said inclined portion along said horizontally disposed portion when said slide has been moved out of alinement with said inclined portion.

7. A machine for feeding rivet caps having, in combination, a hopper, a raceway having an inclined portion and a horizontally disposed portion, a slide movable transversely of said inclined portion and adapted to be engaged by the lowermost

rivet cap of a column of rivet caps on said inclined portion and a detent and feed finger operated by said slide adapted to be moved between said lowermost cap and a cap located thereabove and in contact therewith in a direction substantially tangential to said caps whereby said lowermost rivet cap on said inclined portion of said raceway may be forced onto and along the horizontally disposed portion thereof and said rivet cap adjacent to said lowermost rivet cap held against movement on said inclined portion of said raceway when said slide has been moved out of alinement with said inclined portion.

In testimony whereof I have hereunto set my hand in presence of two subscribing witnesses.

ARTHUR R. HAVENER.
